UNITED STATES PATENT OFFICE

WILLIAM A. BESSMER, OF ERIE, PENNSYLVANIA, ASSIGNOR TO HAMMERMILL PAPER CO., OF ERIE, PENNSYLVANIA, A CORPORATION OF PENNSYLVANIA

PULP BEATER

Application filed September 20, 1930. Serial No. 483,265.

This invention relates to paper manufacture and more particularly to beating engines for acting upon the pulp preliminarily to the passage of the latter to a paper machine. Pulp beaters or beating engines commonly comprise a beater roll on a shaft which is supported at its ends on members, termed lighter bars, mounted on suitable frame work. The pulp is passed between the beater roll and a bed plate.

When a thick lap of pulp passes between the bed plate and the beater roll the roll is raised, carrying its shaft out of the bearings on the lighter bars; and, upon the departure of the thick lap from beneath the roll the shaft of the roll drops down upon said bearings, subjecting the lighter bars to sudden jars and occasionally causing the latter to break. My invention provides simple and efficient means for relieving the lighter bars of shocks and for effectively cushioning the movements of said bars. A further feature of the invention resides in provision for positive adjustment of the positions of the lighter bars. Other features of the invention will be hereinafter described and claimed.

In the accompanying drawings:

Fig. 1 is a view in side elevation illustrating an embodiment of my invention.

Fig. 2 is a view in horizontal section on line 2—2 of Fig. 1.

Fig. 3 is a vertical transverse sectional view on line 3—3 of Fig. 1.

Referring to the drawings, a conventional beater roll is indicated diagrammatically at 5 and the associated bed plate at 6. As is customary, the beater roll is carried by and rotates with a shaft 7, which is journaled at opposite ends in bearings on the respective lighter bars. In the drawings I have shown means associated with but one end of the beater roll shaft 7 for supporting the latter but it will be understood that similar supporting means is provided for the opposite end of said shaft, and since the supporting means at the respective ends of the shaft may be duplicates a disclosure of one thereof is sufficient for an understanding of my invention.

The lighter bar 8, as shown, carries a bearing member 9 for the reception of the shaft

7. Said lighter bar is pivotally mounted at one end on the supporting frame 11. A convenient means for this purpose comprises a trunnion 12 on said bar which trunnion is received in pocket 13 on said frame. The opposite end of said lighter bar is provided with an opening 14 through which there extends a vertical adjusting rod 15, having a head 15' for engagement with the lower surface of said end of the bar. Said rod 15, as shown, 55 is provided with a threaded portion 16 for engagement with an interiorly threaded worm wheel 17 mounted between collars 18, 18 on an upward extension 19 of the frame 11. Said worm wheel may be rotated, and the rod 15 and bar 8 thereby adjusted through a worm 20 on a shaft 21, which may be turned through a suitable handle (not shown). Also, the end portion of the lighter bar adjacent the rod 15 may rest upon a bolt 22 60 mounted in the frame 11 and adjustable through nut 23. Any desired position of the lighter bar and parts carried thereby may be determined with precision by adjustment of the bolt 22, while the movement of said bar 65 and parts may be effected through the rod 15. 70

Bolted or otherwise secured to the housing or frame 11 directly below the shaft 7 and bearing member 9 is a stirrup 24. This stirrup supports a spring plate 25 which in turn 80 carries a spring 26. This spring, at its upper end, cooperates with the lighter bar 8 through spring plate 27. When the beater roll is in normal operating position, the spring 26 is under compression, the amount 85 of compression being preferably substantially equal to the maximum upward movement of the roll from normal position. The amount of compression of the spring 26 may be varied, as desired, by adjustment of the bolt 28 90 threaded into the bottom of the stirrup 24 and engaging the spring plate 25.

When a thick lap of pulp passes between the bed plate 6 and beater roll 5, said roll is raised and the spring 26 causes the lighter 95 bar 8 to follow the upward movement of the roll 5 and shaft 7. After the thick piece of pulp has passed over the bed plate the spring 26 cushions the lighter bar 8, shaft 7, and roll 5 during their return to their lower or 100

normal position, and prevents the lighter bar from receiving sudden shocks or jars.

The terms and expressions which I have employed are used as terms of description and not of limitation, and I have no intention, in the use of such terms and expressions, of excluding any equivalents of the features shown and described or portions thereof, but recognize that various modifications are possible 10 within the scope of the invention claimed.

I claim:

1. In combination, a frame, a lighter bar movably mounted on said frame, a beater roll supported by said bar, and a spring cooperating 15 with said bar intermediate the ends thereof.

2. In combination, a frame, a lighter bar pivotally connected at one end to said frame, means on said frame cooperating with the 20 opposite end of said bar for supporting the latter, bearing means on said lighter bar, a beater roll having a shaft supported on said bearing means, a spring bearing at one end against an intermediate portion of said 25 lighter bar, and means on said frame for supporting the other end of said spring.

3. In combination, a frame, a lighter bar pivotally connected at one end to said frame, means on said frame cooperating with the 30 opposite end of said bar for supporting the latter, bearing means on said lighter bar, a beater roll having a shaft supported on said bearing means, and a spring bearing at one 35 end against said lighter bar directly below said bearing means for cushioning movements 40 of said bar.

4. In combination, a frame, a lighter bar pivotally connected at one end to said frame, means on said frame cooperating with the 45 opposite end of said bar for supporting the latter, bearing means on said lighter bar, a beater roll having a shaft supported on said bearing means, a spring bearing at one end against an intermediate portion of said 50 lighter bar, and means depending from said frame for supporting the other end of said spring.

In testimony whereof, I have signed my name to this specification this 15th day of September, 1930.

WM. A. BESSMER.
